UNITED STATES PATENT OFFICE.

JOHN C. PACKARD, OF DENVER, COLORADO, ASSIGNOR, BY DIRECT AND MESNE ASSIGNMENTS, TO THE ROTARY PUMP COMPANY, OF DENVER, COLORADO, A CORPORATION OF COLORADO.

ROTARY PUMP.

Application filed June 4, 1921. Serial No. 475,128.

My invention relates to improvements in rotary pumps, my object being to provide a thoroughly practicable construction of this character and which shall at the same time be comparatively economical in construction.

Generally speaking the device consists of a casing having formed therein a cylindrical chamber, the casing being provided at each end with a crescent shaped member while between these crescent shaped members is an abutment extending the entire length of the casing, the crescent shaped members and the abutment being integral with the casing. The abutment divides the inlet compartment from the exit compartment of the cylindrical chamber. Journalized within the heads of this casing is a rotor which is tangential to the abutment and thus constantly cooperates with the abutment and the adjacent portions of the crescent shaped members to divide the inlet compartment from the outlet compartment of the chamber when the pump is in operation. The rotor is provided with pockets in which are mounted buckets which have an oscillatory movement in the pockets, the buckets being so disposed within the pockets and the rotor being so mounted and constructed with reference to the inlet and discharge openings of the casing, that the buckets open on the inlet side and discharge on the exit side of the chamber. The opening of the buckets is thus automatic and the closing of the buckets is also automatic, at least to a certain extent since after having performed their function, they have a tendency to move into the pockets by gravity on the exit side of the chamber, but they are positively moved into the pockets by the crescent shaped members and the abutment to which the rotor is tangential as heretofore explained.

Each bucket is provided with an adjustable brace or keeper which is rigidly connected therewith and which passes through a slot formed in the adjacent part of the rotor, the said brace or keeper being provided with an adjustable nut whereby the brace may be made to control the outward movement of the bucket as desired, otherwise during the liquid lifting movement of the bucket there would be a tendency to force the latter outwardly against the inner

wall of the casing to such an extent as to produce undue friction. However by means of the brace or keeper connected with each bucket the latter may be adjustably controlled as heretofore indicated so that if desired there may be an actual clearance between the bucket and the inner wall of the casing when the bucket is open.

Each bucket is provided with a bearing part which engages the adjacent wall of the pocket the said bearings extending beyond the buckets at both ends and being journaled in discs which are mounted within the casing adjacent the ends of the rotor and between the rotor and the detachable heads of the casing. Further, the body of the casing is counterbored at each end forming shoulders which the outer portions of the discs engage, the discs being thus held between the shoulders of the cylindrical part of the casing and the detachable heads of the latter.

Having briefly outlined my improvement I will proceed to describe the same in detail, reference being made to the accompanying drawing in which is illustrated an embodiment thereof.

In this drawing:

Fig. 1 is a detail view of the rotor.

Fig. 1^a is an end elevation of one form of bucket.

Fig. 2 is an elevation of the same or a view looking in the direction of arrow 2 Fig. 1.

Fig. 3 is an end elevation of one of the buckets.

Fig. 4 is an elevation viewed at right angles to Fig. 3 or a view looking in the direction of the arrow 4, Fig. 3.

Fig. 5 is a detail view of one of the end discs carried by the rotor.

Fig. 6 is a section taken on the line 6—6 of Fig. 5.

Fig. 7 is an end elevation partly in section of my improved pump, one of the detachable heads of the casing and one of the end discs of the rotor being removed.

Fig. 8 is a view partly in elevation looking in the direction of arrow 8, Fig. 7, and partly in section taken on the line 8—8 Fig. 7.

The same reference characters indicate the same parts in all the views.

Let the numeral 5 designate the casing of

2
my improved pump considered in its entirety and composed of a cylindrical member 6 and detachable heads 7 connected with the cylindrical member by suitable fastening devices as stud bolts 8. Within this casing and formed integral therewith are two crescent shaped members 9, one being located on each end of the chamber, while extending between the central and lower portions of these members is an abutment 10 which forms a sort of division in the lower part of the casing chamber between the inlet 12 and the outlet 13 of the casing.

15 Mounted within the cylindrical chamber of the casing is a rotor 14 which is fast on a shaft whose ends extend beyond the rotor and are journalled in hubs 16 formed on the detachable heads 7, the said heads being provided with stuffing boxes 17 whereby tight joints are formed around the journals. This rotor is approximately cylindrical in shape and is centrally mounted in the chamber, being of such size, however, that it is tangential to the abutment 10 and the adjacent portions of the crescent shaped members 9, whereby the inlet and outlet compartments of the chamber are separated from each other. Within this rotor a number of pockets 18 which are equi-distantly spaced around the rotor and are open to receive buckets 19 which are arranged to oscillate within the said pockets, each bucket having a bearing edge 20 which projects slightly beyond the rotor at both extremities 30 as shown at 21, these projections being journalled in recesses 22 formed in discs 23, the said discs being secured to the opposite extremities of the rotor by screws or bolts 24 or other suitable fastening device. The cylindrical part 6 of the casing is counter-bored at each end as shown at 25, forming shoulders against which the outer portions of the discs 23 bear, the said discs being held in their proper positions by means of 35 ribs 26 formed on the heads 7, the said ribs being arranged in opposing relation to the shoulders formed by the counter-bores 25 in the casing. The discs, however, are free to move between the ribs 26 and the 40 said shoulders during the operation of the pump as they must move with the rotor. The faces of the buckets or the surfaces remote from the bearings 20, are curved as 45 shown at 27 or otherwise suitably shaped to act upon the liquid to be handled, while the outer surfaces 28 of the buckets are curved inwardly slightly from the outer edge 29 of the operating face of the bucket so that the surface 28 shall not conform to 50 the curve of the outer surface of the rotor. By virtue of this construction, the edge 29 of the bucket is allowed to swing outwardly into contact with the inner surface of the chamber, just as soon as the face of the 55 bucket leaves the tangential line of the abut- 60

ment 10, whereas, if the face 28 of the bucket were curved to conform to the curvature of the rotor, the operating extremity of the bucket could not swing outwardly into contact with the inner face of the chamber until the entire length of the bucket had passed beyond the tangential line of the abutment, and as soon as this occurred, the bucket would be thrown suddenly outwardly with a pounding result. By curving the surface 75 28 of the bucket as heretofore described, I 80 avoid this difficulty.

Further, connected with each bucket is a bolt 30 which forms a sort of brace or keeper, the said bolt passing thru a slot 31 85 formed in the web of the rotor which separates the pocket 18 from a cavity 32 formed longitudinally through the rotor. To the inner extremity of the bolt 30 or the extremity which projects into the cavity 32, is applied a nut 33 which is adjustable on the bolt which is threaded for the purpose, whereby the outward movement of the bucket toward the inner surface of the casing chamber, may be controlled since the nut 90 forms a stop for said purpose, the width of the slot 31 being less than that of the nut. If desired, this nut may be so adjusted as to leave a slight clearance between the inner surface of the chamber and the edge 95 29 of the bucket. In the absence of a feature of this character, the pressure of the water upon the face 27 of the bucket would have a tendency to force the latter outwardly against the adjacent surface of the casing, whereby a large amount of friction 100 might result.

It should be explained that other means may be employed to perform this function. For instance, the inner edge 34 of the bucket 105 may be made to engage a lip 35 formed on the rotor whereby the outward movement of the bucket is predetermined. However, in this structure no adjustment is permissible hence bolt 30 and the other parts 110 operating therewith, are believed preferable. The modified form of construction is, however, shown as it is exceedingly simple and may be found commercially practicable.

Another important feature of my improved pump, consists in the construction and arrangement of the casing on the inlet and discharge sides, whereby both of the openings are large and of rectangular shape so that the least possible resistance is present to the inlet and discharge of the water. The inlet opening 12 is fully illustrated in Fig. 7, in which the outlet opening 13 is also indicated to some extent since it extends from the dotted line 36 to the bottom 120 wall 37. By having this opening large and rectangular in shape, as shown in Fig. 8, the water under the propelling action of the buckets, passes freely out of the casing, there being no retarding structure. It 125 130

should, however, be explained that the number of buckets should be such that a bucket in the rear will have passed the top of the inlet opening before the bucket immediately 5 in advance passes beyond the upper part of the discharge opening, since the rear bucket must catch the water on the inlet side at least as early as the bucket in advance reaches the discharge opening of the 10 casing.

Attention is called to the fact that each bucket is provided with one or more openings 38 adjacent the bearing edge 20 which allow the water to circulate freely between 15 the pocket and the chamber outside of the rotor, thus preventing any retarding action due to suction which might offer resistance to the outward movement of the buckets, and further, by allowing the water to enter the 20 pockets, a certain balancing effect is present. By locating the openings 38 adjacent the bearing edge 20 the pressure of the water on the outlet side of abutment 10 will have effect upon the inner side of bucket 19 until a substantial part of the bucket has passed the 25 abutment. As the pressure on the outlet side is considerably greater than that upon the inlet side, it is obvious that this pressure will operate behind bucket 19 to force the 30 buckets out from the pockets.

It will be understood from the foregoing that the pockets 18 extend the entire length of the rotor between the discs 23, and this is also true of the buckets which operate 35 within the pockets.

From the foregoing description the use and operation of my improved rotary pump will be readily understood. Assuming that the parts are assembled as illustrated in the 40 drawing (see Figs. 7 and 8), as the rotor is moved within the chamber of the casing, each bucket, as it passes the tangential line or the line of contact between the rotor and the abutment 10, begins to open and pick up the water on the inlet side of the chamber, 45 and the bucket continues to move outwardly and maintain such a position that its outer edge 29 is sufficiently close to the inner sur-

face of the casing as to prevent the escape of the water. As the rotor continues its 50 travel, the bucket forces the water between the rotor and the casing forwardly in the direction of arrow "a" which is the direction of the rotor's travel, until the discharge opening 13 is reached, after which there is a 55 tendency for the bucket to move into its pocket by gravity, until the points 39 are reached where the crescent shaped members 9 begin, after which the bucket is positively moved inwardly until the tangential or center 60 line of the abutment 10 is reached after which the bucket begins to open, as heretofore explained, the opening movement being accomplished by gravity, and the resistance of the water which also acts to perform this function as soon as the bucket commences to pick up the water on the inlet side of the chamber. 65

I claim:

1. A rotary pump comprising a casing 70 enclosing a cylindrical chamber having an abutment, a rotor journaled in the casing and engaging the abutment but leaving a space between the rotor and the casing at all other points, the rotor having pockets, and buckets 75 hingedly connected with the rotor to move into and out of said pockets, the outer faces of the buckets being curved inwardly to permit them to swing outwardly rapidly for passing the abutment. 80

2. In a rotary pump having a casing, a rotor provided with pockets and oscillatory buckets mounted in said pockets, means for admitting to the pockets hydraulic pressure from without the rotor to start said buckets 85 out of the pockets.

3. In a rotary pump of the character described having an abutment member, a bucket member having a pivotal bearing edge and an operative face, and a passage 90 through said bucket spaced from the operative face more than the width of the abutment.

In testimony whereof I affix my signature.

JOHN C. PACKARD.
